UNITED STATES PATENT OFFICE.

SAMUEL HARRISON EVERETT, OF BROOKLYN, NEW YORK, ASSIGNOR TO WESTERN ELECTRIC COMPANY, INCORPORATED, OF NEW YORK, N. Y., A CORPORATION OF NEW YORK.

ELECTROMAGNETIC SWITCHING DEVICE OR RELAY.

1,278,448.

Specification of Letters Patent. Patented Sept. 10, 1918.

Original application filed March 11, 1915, Serial No. 13,696. Divided and this application filed August 20, 1917. Serial No. 187,281.

To all whom it may concern:

Be it known that I, SAMUEL H. EVERETT, a citizen of the United States, residing at Brooklyn, in the county of Kings and State 5 of New York, have invented certain new and useful Improvements in Electromagnetic Switching Devices or Relays, of which the following is a full, clear, concise, and exact description.

10 This invention relates to electromagnetic devices or relays and more particularly to such devices which are subjected to alternating currents of widely different frequencies, to direct current alone, or to direct 15 current upon which is superimposed alternating currents of widely different frequencies.

This application is a division of my co-pending application, Serial No. 13,696, filed 20 March 11, 1915, and assigned to the same assignee as the present application.

The object of this invention is to provide a relay which will operate on direct current alone or on direct current upon which is 25 superimposed alternating currents of widely different frequencies but which will not operate upon any of those alternating currents alone of values experienced in service.

This result is accomplished by providing 30 a relay having a core upon which there is an energizing winding positioned intermediate the ends of the core, with supplementary closed circuited coils or non-magnetic hollow cylindrical members surrounding the core 35 and located upon each side of the energizing winding. Preferably these closed circuited coils consist of large masses of copper. These coils are so proportioned and the energizing winding so positioned that the leakage and 40 demagnetization effects due to them will be such as to permit of the operation of the relay on direct current alone or on direct current upon which is superimposed alternating currents of any frequency, but will 45 not allow of its operation upon alternating currents alone.

The invention will be more clearly understood by reference to the accompanying drawing wherein:

50 Figure 1 is a side elevation of a relay showing one embodiment of this invention; Fig. 2 is a side elevation, partly in section, of the relay of Fig. 1; Fig. 3 is a similar

section showing a modification of the short-circuited windings, and Fig. 4 shows a 55 multi-frequency telephone signaling circuit employing the relay of this invention.

As shown in Figs. 1 and 2 the relay may consist of a core 5, about which is placed an energizing winding 6 positioned intermediate the ends of the core 5. There is also mounted upon the core 5 short circuited coils 7 and 8, one on each side of the energizing winding 6. These short circuited coils 7 and 8 consist preferably of non-magnetic hollow cylindrical masses of copper. The energizing winding 6 and core 5 and the closed circuited coils 7 and 8 may be suitably separated by means of insulating material 9. At one end of the core is provided a collar 10 separated from the closed circuited coil 7 by an insulating washer 11. On the washer 11 there may be located terminals 15 and 16 suitably mounted, to which are attached leads from the energizing 70 winding 6. The core 5, together with the above described parts mounted thereon, may be inclosed in a shell 17 of magnetic material, openings being provided in the closed end 18 thereof, with which register the terminals 15 and 16 and the end of the core 5.

The core 5 is firmly secured to the closed end 18 of the shell 17 by means of a nut 19 having screw-threaded engagement with the end of the core. The terminal 20 to which 85 one lead of a control circuit may be attached, is suitably secured to the core 5. Near the open end of the shell 17 there is mounted upon the shell a yoke 21 of non-magnetic material to which is pivoted an 90 armature 22 in operative relation to the free end of the core 5. A spiral spring 25 secured at one end to a finger 26 mounted on a shell 17 and at the other end to a finger 27 attached to the armature 22, normally 95 holds the armature 22 away from the end of the core 5 as in Fig. 1. A contact spring 28 mounted on the armature 22 is electrically connected to the terminal 20 through the relay structure. The terminal member 100 29, to which is attached the other lead of the circuit to be controlled, is mounted upon but insulated from the shell 17. In the forward end of terminal member 29, which is bent as shown in Fig. 1 may be mounted 105 an adjustable contact stud 30. Normally

the action of spring 25 maintains contact spring 28 and contact stud 30 in engagement.

In the modification of Fig. 3 the short-circuited windings 7 and 8 are replaced by a number of non-magnetic metallic washers positioned on either side of the energizing winding 6; otherwise the relay structure is the same as that of Fig. 2 and identical parts are designated by identical reference characters.

The dimensions of the important elements of an actual relay made up in accordance with this invention are as follows:

15	Length of core 5 from collar 10 to armature end	3.14"
	Diameter of core 5	3/16"
	Length of closed coil 7	0.78"
20	Diameter of closed coil 7	0.715"
	Length of closed coil 8	1.687"
	Diameter of closed coil 8	0.870"

The energizing winding consists of 3300 turns of No. 35 insulated copper wire.

25 One important use for the relay of this invention is shown in the multi-frequency telephone signaling circuit of Fig. 4 wherein it is designated by the reference character 42. The function of this relay in that circuit is to automatically cause the disconnection of the ringing current from the subscriber's line upon the response of any subscriber by the removal of his receiver from its hook. In order to accomplish this result the relay must not operate on alternating current supplied by the multi-frequency sources of current 51, 52, 53 and 54; but it must operate upon direct current alone supplied by battery 48 or upon direct current 40 upon which is superimposed alternating current of any of the frequencies supplied by said sources of ringing current. The operation of the system of Fig. 4 is briefly as follows:

45 Upon insertion of the calling plug into the jack 35 of the wanted subscriber's line, a circuit is completed from battery 36, through the winding of relay 37, sleeve contacts of the calling plug and jack 35 and 50 the windings of the usual cutoff relay 38 to ground, operating relay 38, thereby removing the usual line relay 39 from the limbs of the subscriber's telephone line. Current in the above path also actuates 55 relay 37, which completes a circuit from battery 36, through contact 40 of relay 37, contact 41 of relay 42, contact 43 of relay 44, and winding of relay 45 to ground, actuating relay 45, which opens the tip and 60 ring strands of the cord circuit and connects the tip side to ground at contact 46 and the ring side through the winding of tripping relay 42 at contact 47.

By means of the multi-party key 49 any 65 one of the sources of alternating current 51,

52, 53 or 54 may be connected to the tip side of the line through the winding of relay 42 and to ground through interrupter 50 and battery 48. Each of the alternating current sources is shunted by an interrupter 56 so positioned with respect to interrupter 50 that its circuit is open, while the circuit through interrupter 50 is closed, and vice versa.

After the insertion of the calling plug 75 into the jack 35 of the wanted line, the operator operates a button of the locking ring-key 49 connecting to one of the middle contacts of this key alternating current of the frequency to which the bell at the 80 wanted substation is turned. Suppose that the left-hand contact of key 49 has been closed, a circuit is then completed from grounded battery 48, through the interrupter 50, generator 51, or through the interrupter 85 56, depending upon the relative positions of the interrupters 50 and 56, left-hand alternate contact of the ringing key 49, winding of the tripping relay 42, alternate closed contact 47 of relay 45, ring side of the line, 90 bells 60, 62, 64 and 66, and condensers 61, 63, 65 and 67 in parallel, tip side of the line and alternate contact 46 of relay 45 to ground. Only one of the bells, say 60, responds to this current, since it alone is 95 tuned to respond to the frequency of source 51. The condenser 61 at the subscriber's station prevents the passage of direct current. Tripping relay 42, therefore, does not operate when in series with the bells 60, 62, 64 and 66 and the condensers 61, 63, 65 and 67.

When, however, the receiver at one of the subscriber's stations is removed from the switchhook, a low resistance path in shunt 105 with the bells and condensers is closed, whereupon tripping relay 42 operates, opening the short circuit of relay 44. Relay 44 thereupon operates and locks up, short-circuiting relay 45, which releases to disconnect the ringing current from the line. The removal of the receiver at the called subscriber's station either during the period when direct current alone is connected to the line or during the period when direct 115 current upon which is superimposed alternating current of any of the different frequencies is connected thereto causes the tripping relay 42 to operate. It is, therefore, clear that to function properly the relay 42 must not operate when the receiver is on the hook and alternating current of any of the different frequencies is alone connected to the line, but must operate when the receiver is off and either direct current alone 120 or direct current upon which is superimposed any of the various frequencies is connected thereto.

Relays have been produced heretofore to operate when traversed by direct current 130

alone or by direct current upon which is superimposed alternating current of a single frequency, and not to operate when traversed alone by alternating current of that particular frequency; but no relay has heretofore been produced, which would operate, as hereinbefore described, when alternating current of any of a plurality of widely different frequencies was being used.

Such a relay is of very great importance and utility in multi-frequency ringing circuits of telephone signaling systems, such as herein described. In heretofore known systems, it has been necessary to use a separate tripping relay in a cord or telephone circuit for each frequency of alternating current, while now it is possible by the utilization of the tripping relay embodying the present invention to employ only one tripping relay in a cord or trunk circuit to accomplish the same result.

What is claimed is:

1. In a relay comprising a core and an armature mounted adjacent to one end of said core, an energizing winding at an intermediate position on said core and a pair of short-circuited windings for said core, one at each side of said energizing winding.
2. In a relay comprising a core and an armature mounted adjacent to one end of said core, an energizing winding at an intermediate position on said core, and a pair of nonmagnetic conducting hollow cylindrical members completely surrounding said core, one at each side of said energizing winding.
3. In a relay comprising a core, and an armature mounted adjacent to one end of said core, an energizing winding at an intermediate position on said core and a plurality of non-magnetic conducting washers surrounding said core on both sides of said energizing winding.
4. In a relay, a tubular magnetic member open at one end, a magnetic core within said member, an energizing winding at an intermediate position on said core, a hollow cylindrical non-magnetic conducting mem-

ber surrounding said core adjacent to one side of said energizing winding, a second hollow cylindrical non-magnetic conducting member adjacent to the opposite side of said winding, and an armature adjacent to said core at the open end of said tubular member.

5. In a relay, a tubular magnetic member open at one end, a magnetic core within said member, an energizing winding at an intermediate position on said core, a short-circuited winding for said core at one side of said energizing winding, a second short-circuited winding for said core at the other side of said energizing winding and an armature adjacent to said core at the open end of said tubular member.

6. In a relay, a tubular magnetic member open at one end, a magnetic core within said member, an energizing winding at an intermediate position on said core, a plurality of non-magnetic conducting washers surrounding said core located on both sides of said energizing winding, and an armature adjacent to said core at the open end of said tubular member.

7. In a relay for use in a circuit comprising sources of direct current and of multi-frequency alternating current, a core, an energizing winding thereon, an armature in operating relation to said core and demagnetizing means energizable by alternating currents of any of the different frequencies from the multi frequency source to prevent the core from attracting its armature under the influence of said currents, said means being non-responsive to the direct current, and said energizing winding being adjusted to enable the direct current to energize said core sufficiently to attract its armature irrespective of the passage of said alternating currents.

In witness whereof, I hereunto subscribe my name this 17th day of August, A. D. 1917.

SAMUEL HARRISON EVERETT.
